UNITED STATES PATENT OFFICE.

HERBERT C. SMITH, OF FOREST GROVE, OREGON.

LUBRICATOR.

1,367,211.

Specification of Letters Patent.

Patented Feb. 1, 1921.

Application filed March 8, 1920. Serial No. 364,212.

To all whom it may concern:

Be it known that I, HERBERT C. SMITH, a citizen of the United States, residing at Forest Grove, in the county of Washington and State of Oregon, have invented certain new and useful Improvements in Lubricators; and I do declare the following to be a full, clear and exact description of the invention, such as will enable others skilled in the art to which it appertains to make and use the same.

My invention relates to improvements in lubricating devices and more particularly to those which are intended primarily for lubricating gear wheels, sprockets, sprocket chains, etc. Brushes have heretofore been employed for this purpose having means for feeding the lubricant thereto, but these devices have been objectionable in that no provision has been made for renewing the brushes when they are worn to a condemning degree. My invention, however, aims to overcome this difficulty by the provision of an extremely simple and inexpensive, yet a highly efficient and durable arrangement of parts for detachably securing the brush or brushes to the lubricant feed pipe. By this arrangement, whenever a brush is no longer of use, it may be removed and a new one substituted.

Another object is to make novel provision for cleaning the lubricant outlet openings of the feed pipe, and with this and minor objects in view, the invention resides in the novel features of construction and arrangement of parts hereinafter described and claimed.

Figure 1, of the accompanying drawings, is a side elevation of my invention showing its application for lubricating a gear wheel.

Fig. 2 is an end elevation of the device shown in Fig. 1.

Fig. 3 is an enlarged side elevation of the lubricator.

Fig. 4 is a central longitudinal sectional view.

Fig. 5 is a transverse section on the plane indicated by line 5—5 of Fig. 4.

Fig. 6 is a top plan view.

In carrying out my invention I prefer to make use of the several details of construction hereinafter described and fully shown in the accompanying drawing, but it is obvious that numerous minor changes and modifications may well be made.

On the drawing the numeral 1 designates

a lubricant feed pipe which may well be rather short and coupled at 2 to a suitably supported supply pipe 3 leading from any preferred lubricant container 4. I have shown a pair of brushes 5 having backs 6 contacting with opposite sides of the pipe 1, and said backs are preferably formed with longitudinal grooves or seats 7 receiving said pipe. For detachably securing the brush backs 6 to the pipe 1, I prefer to employ an arched holder 8 which straddles said pipe and backs, as shown clearly in Figs. 2 and 5. The central portion of the holder 8 is by preference riveted or otherwise secured to pipe 1, as shown at 9, while its side flanges 10 contact with the sides of the brush backs 6, opposite those which engage the pipe 1. Frictional contact may be relied upon to hold the brush backs 6 in place between the flanges 10 and the pipe 1, but I prefer that screws 11 shall be employed for this purpose. Between the two brushes, the pipe 1 is shown provided with a plurality of longitudinally spaced lubricant outlet openings 12. The lubricant discharged from these openings is received upon the brushes 5 and is thus carried to the gear or the like to be lubricated. In order that a suitable instrument may be forced outwardly through the openings 12 for cleaning whenever required, I prefer that the side of the pipe 1 opposite said openings, as well as the holder 8, shall be provided with openings 13 aligned with said openings 12. These openings 13 are normally closed by any preferred means and when such means is removed an instrument of any suitable sort may be inserted through the openings 13 and passed outwardly through the openings 12, thus unclogging the latter. For normally closing the openings 13, I have shown a plate 14 secured by screws or the like 15 to the holder 8 and provided with plugs 16 entering the openings of said holder. It will be understood, however, that any other suitable opening-closing means could well be used.

I have shown the free end of the pipe 1 closed by a removable plug 17, which plug may be removed from time to time to permit cleaning of the entire pipe. It will be understood however that this detail need not be used unless desired.

In operation, the lubricator is suitably supported, for instance as indicated in Fig. 1, with brushes 5 disposed for contact with the gear wheel or other machine part to be

lubricated. The lubricant supplied through the pipe 1 is discharged from its openings 12 onto the brushes and is carried by the latter to the wheel or the like, and it will be understood that any adequate lubricant may be used. Whenever one or both of the brushes have been worn to an objectionable extent, said brush or brushes may be easily removed so that new ones can be substituted. This 10 constitutes an important advantage over similar lubricating devices which have heretofore been used, provided however with no details of construction permitting the renewal of worn brushes. The entire device 15 may be cleaned when necessary by uncovering the openings 13 and inserting a suitable instrument as above described, and by uncorking the pipe 1 if found necessary.

This device is extremely simple and inexpensive, yet it is highly efficient and in every way desirable, and since probably the best results may be obtained from the details disclosed, such details may well be followed. I wish it understood however that within the 25 scope of the invention as claimed, numerous modifications may be made, and in some instances only one brush and half of the holder 8 need be used, if it should be desirable to do so.

30 I claim:

1. A lubricator comprising a pipe to connect with a source of lubricant supply, a pair of brushes having backs contacting with opposite sides of the pipe, and means for removably holding said backs in place, said pipe having a lubricant outlet between said brushes.
2. A lubricator comprising a pipe to connect with a source of lubricant supply, a pair of brushes having backs contacting with opposite sides of the pipe, and an arched holder straddling said pipe and backs to retain them in fixed relation, said pipe having a lubricant outlet between said brushes.
3. A lubricator comprising a pipe to connect with a source of lubricant supply, a pair of brushes having backs at opposite sides of said pipe and grooved to receive said pipe, and an arched holder straddling said

pipe and backs to secure the latter in place, 50 said pipe having a lubricant outlet between said brushes.

4. A lubricator comprising a rigidly supported pipe to connect with a source of lubricant supply, a brush having a back provided with a groove to partially receive said pipe, and means for detachably securing said pipe and back together and supporting the latter from the former, said pipe having means for supplying a lubricant to said 60 brush.

5. A lubricator comprising a rigidly supported pipe to connect with a source of lubricant supply, a brush having a back contacting with one side of said pipe, and means 65 for detachably securing said brush back and pipe together and supporting the former from the latter, said pipe having means for supplying a lubricant to said brush.

6. A lubricator comprising a rigidly supported pipe to connect with a source of lubricant supply, a brush having a back in contact with said pipe, and a holding plate for said back extending outwardly from the pipe and laterally in contact with the side 75 of the brush back opposite to said pipe, the latter having a lubricant outlet adjacent said brush.

7. A lubricator comprising a rigidly supported pipe to connect with a source of 80 lubricant supply, brushes having backs in contact with opposite sides of said pipe, an arched holder secured to said pipe and straddling said pipe and brush back to hold them in fixed relation, said pipe having 85 lubricant openings between the brushes and said holder and pipe having other openings aligned with said outlet openings to receive a cleaning device, and means for normally closing said openings in the holder. 90

8. The structure specified in claim 7, said opening-closing means comprising a plate secured to said holder and having plugs received in the openings thereof.

In testimony whereof I have hereunto set my hand.

HERBERT C. SMITH.
